FEED MECHANISM FOR PERFORATED TAPE CONTROLLED APPARATUS

Henry L. Tholstrup, Rochester, N. Y., assignor, by mesne assignments, to the United States of America as represented by the Secretary of the Navy

Application June 24, 1955, Serial No. 517,949

6 Claims. (Cl. 197—20)

This invention relates to feed mechanisms employed in perforated-tape-controlled apparatus, such as typewriters, computer input and output devices, etc., and, more particularly, to such feed mechanism utilizing a ratchet wheel in cooperation with a cam operated pawl for intermittently feeding perforated tape.

Perforated-tape-controlled apparatus is well known in the art and a typical example of such apparatus is fully disclosed in my Patent 2,448,842. The perforated tape feed mechanism disclosed in this patent, and shown in Figs. 2 and 4 thereof, incorporates a relatively complex multiple linkage between the cam wheel and the pawl actuating the ratchet wheel. In addition to this patent, other types of feed mechanisms for advancing perforated tape are shown in Fig. 3 of Patent 2,346,267 issued to Mills et al., and in Figs. 1 and 2 of Patent 2,279,161, issued to D'Humy. The feed mechanisms disclosed in these latter two patents also incorporate a multiple linkage between the cam wheel and the pawl actuating the ratchet wheel.

It is an object of this invention to provide a linkage between the cam wheel and the ratchet wheel which gives improved reliability of operation.

It is a more specific object of this invention to provide a rigid one-piece link which is integral with the pawl actuating the ratchet wheel.

Other objects and many of the attendant advantages of this invention will be readily appreciated as the same becomes better understood by reference to the following detailed description when considered in connection with the accompanying drawings wherein:

Fig. 1 is an elevation view of a feed mechanism incorporating the principles of this invention, and

Fig. 2 is a section of Fig. 1 along line 2—2.

Referring now to Figs. 1 and 2, there is shown high point cam wheel 10 which is fixedly attached to drive shaft 12. At a distance from drive shaft 12, but disposed parallel thereto, is feed shaft 14. Mounted on feed shaft 14, and coaxial therewith, is first member 16 which incorporates as an integral part thereof ratchet wheel 18. Also included as parts of first member 16 are reduced diameter portion 20 located immediately adjacent ratchet wheel 18 and shoulder 21 located next to reduced diameter portion 20.

Linking cam wheel 10 to ratchet wheel 18 is second member 22. Second member 22 consists of a first relatively thin rigid flat strip 24. A second thin rigid flat strip 26 is fixedly attached to first strip 24 and is oriented, as shown, with most of its length parallel to first strip 24. U-shaped slot 28 is cut in one end of each of first and second strips 24 and 26. Cam wheel 10 is disposed between strips 24 and 26, as shown, and drive shaft 12 is received on either side of cam wheel 10 by the respective slot 28 of each of first and second strips 24 and 26. Rotatably mounted on a pin passing between rivets 30 is cam follower 32. Cam follower 32 is positioned as shown to engage cam wheel 10.

At the other end of first strip 24 is slot 33. Slot 33

2

receives reduced diameter portion 20, which has an axial extent just sufficient to accommodate the thickness of first strip 24. An extension from first strip 24 forms a short tab 34 which is bent at substantially a right angle. The position of tab 34 on first strip 24 relative to the position of ratchet wheel 18 is such as to permit tab 34 to engage a tooth of ratchet wheel 18.

Also mounted on feed shaft 14, and coaxial therewith, are detent wheel 36 and sleeve 38 which includes tape feed sprocket 40. Cooperating with detent wheel 36 is detent assembly 41.

Spring 42 connects second member 22 to a fixed point on the apparatus.

In operation, once each revolution of drive shaft 12 the high point of cam wheel 10 comes in contact with cam follower 32. This causes second member 22 to be reciprocated upward, pushing tab 34, which acts as a pawl, against tooth of ratchet wheel 18, thereby pushing ratchet wheel 18 one space forward. Detent wheel 36 and detent 41 coat in a conventional manner to maintain feed shaft 14 in its new position. This results in sprocket 40 advancing the perforated tape one space.

After the high point of cam wheel 10 passes cam follower 32, second member 22 is reciprocated downward under the action of spring 42 which maintains cam follower 32 in contact with cam wheel 10 and also maintains tab 34 in contact with ratchet wheel 18.

It will readily be seen that the single piece link disclosed herein is much simpler than the multiple link feeding mechanisms disclosed in the above-mentioned patents. Also the play between the multiple links is eliminated, which results in a feed mechanism having an improved reliability of operation.

Obviously many modifications and variations of the present invention are possible in the light of the above teachings. It is therefore to be understood that within the scope of the appended claims the invention may be practiced otherwise than as specifically described.

I claim:

40. 1. In combination with apparatus employing a perforated tape, a feeding mechanism for said tape comprising a feed shaft and a drive shaft, said shafts being substantially parallel to each other, a first member including a ratchet wheel mounted on and coaxial with said feed shaft, a high point cam wheel mounted on said drive shaft; and a rigid second member having a cam follower rotatably pinned toward one end thereof and a pawl portion integral with said second member toward the other end thereof, said second member being oriented with said cam follower in cooperative engagement with said cam wheel and said pawl portion in cooperative engagement with a tooth of said ratchet wheel, whereby said second member forms a single link between said cam wheel and said ratchet wheel, said second member including a first relatively thin rigid flat strip, a second relatively thin rigid flat strip of shorter length than said first strip positioned to have one end thereof opposite said one end of said first strip, said second strip being oriented parallel to said first strip and being spaced therefrom by an amount greater than the width of said cam wheel, means fixedly attaching said second strip to said first strip, said first and second strips each having a first slot in said one end thereof and said first strip having a second slot in said other end thereof, said cam wheel lying between said first and second strips and said drive shaft being received on opposite sides of said cam wheel by each of said first slots respectively, said first member further including an extension coaxial with said feed shaft having a reduced diameter portion immediately adjacent said ratchet wheel which is less than the width of said second slot and a shoulder having a diameter which is greater than the width of said second slot termi-

nating said reduced diameter portion, the axial extent of said reduced diameter portion being just sufficient to receive the thickness of said first strip and said reduced diameter portion being received by said second slot, and said pawl portion comprising a short tab fixedly attached near said other end of said first strip and extending at substantially a right angle therefrom to cooperatively engage a tooth of said ratchet wheel.

2. The feeding mechanism defined in claim 1, further comprising spring means connecting said second member to a fixed point, said spring means being oriented to apply a force in a direction which urges said tab into positive contact with a tooth of said ratchet wheel and urges said cam follower into positive contact with said cam wheel.

3. In apparatus employing a perforated tape; a feeding mechanism for said tape comprising a feed shaft and a drive shaft, said shafts being substantially parallel to each other, a first member including a ratchet wheel mounted on and coaxial with said feed shaft, a high-point cam wheel mounted on said drive shaft, and a rigid second member having a cam follower rotatably pinned toward one end thereof and a pawl portion integral with said second member toward the other end thereof, said second member being oriented with said cam follower in cooperative engagement with said cam wheel and said pawl portion in cooperative engagement with a tooth of said ratchet wheel, whereby said second member forms a single link between said cam wheel and said ratchet wheel, said second member including a first relatively thin rigid flat strip, a second relatively thin rigid flat strip of shorter length than said first strip positioned to have one end thereof opposite said one end of said first strip, said second strip being oriented parallel to said first strip and being spaced therefrom by an amount greater than the width of said cam wheel, means fixedly attaching said second strip to said first strip, said first and second strips each having a first slot in said one end thereof and said first strip having a second slot in said other end thereof, said cam wheel lying between said first and second strips, and said drive shaft being received on opposite sides of said cam wheel by each of said first slots respectively, said first member further including an extension coaxial with said feed shaft having a reduced diameter portion immediately adjacent said ratchet wheel which is less than the width of said second slot and then a shoulder having a diameter which is greater than the width of said second slot terminating said reduced diameter portion, the axial extent of said reduced diameter portion being just sufficient to receive the thickness of said first strip and said reduced diameter portion being received by said second slot, and said pawl portion comprising a short tab fixedly attached near said other end of said first strip and extending at substantially a right angle therefrom to cooperatively engage a tooth of said ratchet wheel.

4. The feeding mechanism defined in claim 3, further comprising spring means connecting said second member to a fixed point, said spring means being oriented to apply a force in a direction to urge said tab into positive contact with a tooth of said ratchet wheel and to urge said cam follower into positive contact with said cam wheel.

5. A tape feeding mechanism adapted for use in ap-

paratus employing a perforated tape, said tape feeding mechanism comprising: a feed shaft; a drive shaft parallel to said feed shaft; a first member including a ratchet wheel portion and a portion contiguous and coaxial therewith of smaller diameter and a shoulder terminating the free end of said smaller diameter portion, said first member being mounted on said feed shaft coaxial therewith; a cam mounted on said drive shaft opposite to said first member; a rigid second member including a first thin rigid flat strip, a second thin rigid flat strip of shorter length than said first strip and secured to said first strip whereby at least a portion of said second strip is parallel to said first strip and whereby the free end of said second strip terminates adjacent one end of said first strip, said first and second strips being formed with aligned slots in their adjacent ends, the other end of said first strip being formed with another slot, and a cam follower rotatably joined to said first and second strips inwardly of the bottoms of said aligned slots, said first strip having an integral pawl portion adjacent said other end thereof, the slotted other end of said first strip registering with the smaller diameter portion of said first member for a sliding fit with the facing surfaces of said ratchet wheel portion and said shoulder, said pawl portion engaging said ratchet wheel, the aligned slots in the adjacent ends of said first and second strips registering with said drive shaft adjacent opposite sides of said cam, and said cam follower engaging said cam; and spring means connected to said second member and to means that is fixed relative to the axes of said shafts to urge said pawl portion into contact with a tooth of said ratchet wheel portion and to urge said cam follower into contact with said cam.

6. A step-by-step feeding mechanism comprising: a feed shaft; a drive shaft parallel to said feed shaft; a first member including a ratchet wheel portion and a portion contiguous and coaxial therewith of smaller diameter and a shoulder terminating the free end of said smaller diameter portion, said first member being mounted on said feed shaft coaxial therewith; a cam mounted on said drive shaft opposite to said first member; a rigid second member formed with a slot at each end thereof and further formed with an integral pawl portion near one of the slotted ends; a cam follower mounted on said second member near the inner end of the other slot; the said one slotted end registering with the smaller diameter portion of said first member for a sliding fit with the facing surfaces of said ratchet wheel portion and said shoulder, said pawl portion engaging said ratchet wheel portion, the other slotted end of said second member registering with said drive shaft adjacent said cam, and said cam follower engaging said cam; and spring means connected to said second member and to means that is fixed relative to the axes of said shafts to urge said pawl portion into contact with a tooth of said ratchet wheel portion and to urge said cam follower into contact with said cam.
